Primary Examiner — Freda S Nunn(74) *Attorney, Agent, or Firm* — Nixon & Vanderhye P.C.(57) **CLAIM**

The ornamental design for a digital information display, as shown and described.

DESCRIPTION

FIG. 1 is a front, right perspective view of a digital information display in accordance with our new design;

FIG. 2 is a front elevation view thereof;

FIG. 3 is a back elevation view thereof;

FIG. 4 is a top plan view thereof;

FIG. 5 is a bottom plan view thereof;

FIG. 6 is a right side elevation view thereof;

FIG. 7 is a left side elevation view thereof; and,

FIG. 8 is a right side sectioned view taken along line 8-8 of FIG. 2.
